HOUSING FOR A REMOTE CONTROL ELECTRONIC THERMOSTAT

Joseph A. Rinaldi, Fort Lee, N.J., assignor to Kimeco
Laboratories, Inc., Brooklyn, N.Y.

Filed Dec. 17, 1969, Ser. No. 20,548

Term of patent 14 years

Int. Cl. D13—03

U.S. Cl. D26—13

FIG. 1

FIG. 2

FIG. 3

FIG. 4

FIG. 5

FIG. 6

FIG. 1 is a perspective view taken from in front and above of the housing for a remote control electronic thermostat, showing my new design;

FIG. 2 is a top plan view of the housing;

FIG. 3 is a front end view;

FIG. 4 is a side elevational view;

FIG. 5 is a bottom plan view; and

FIG. 6 is a rear end view of the housing.

I claim:

The ornamental design for a housing for a remote control electronic thermostat, as shown.
